[57] CLAIM

The ornamental design for a beach towel with pockets, as shown and described.

DESCRIPTION

FIG. 1 is a perspective view of the beach towel with pockets embodying the design of the present invention;

FIG. 2 is a top plan view thereof;

FIG. 3 is a bottom view thereof;

FIG. 4 is a side elevational view thereof, the side opposite being a mirror image of the side shown in FIG. 4;

FIG. 5 is an end elevational view thereof; and,

FIG. 6 is an end elevational view thereof.

The criss-cross pattern fragmentarily shown in FIGS. 1-6, is understood to extend throughout the beach towel.

FIG. 1.

FIG. 6.

FIG. 5

FIG. 4.

FIG. 2.

FIG. 3.
